UNITED STATES PATENT OFFICE.

WILLIAM B. WALKER, OF NEW YORK, N. Y., ASSIGNOR TO AMERICAN THERMOS BOTTLE COMPANY, OF NEW YORK, N. Y., A CORPORATION OF MAINE.

DESIGN FOR A VESSEL-CASE.

48,877.

Specification for Design.

Patented Apr. 11, 1916.

Application filed January 27, 1915. Serial No. 4,801. Term of patent 14 years.

To all whom it may concern:

Be it known that I, WILLIAM B. WALKER, a citizen of the United States, residing in the city, county, and State of New York, have invented a new, original, and ornamental Design for Vessel-Cases, of which the following is a specification, reference being had to the accompanying drawing, forming part thereof.

The figure is an elevation view of a vessel case showing my new design.

I claim:—

The ornamental design for a vessel case, as shown.

WILLIAM B. WALKER.

Witnesses:

ROBERT B. KILLGORE,

MAY M. LIPP.
